UNITED STATES PATENT OFFICE.

NEWTON H. ANDRUS, OF NEBRASKA CITY, NEBRASKA.

DESIGN FOR A HANDLE FOR SPOONS OR SIMILAR ARTICLES.

SPECIFICATION forming part of Design No. 36,095, dated October 7, 1902.

Application filed August 4, 1902. Serial No. 118,416. Term of patent 3½ years.

To all whom it may concern:

Be it known that I, NEWTON H. ANDRUS, a citizen of the United States, residing at Nebraska City, in the county of Otoe and State of Nebraska, have invented and produced a new, original, and ornamental Design for a Handle for Spoons, of which the following is a specification, reference being had to the accompanying drawings, forming part thereof, and in

10 which—

Figure 1 is a view of the front of the spoon embodying my design, and Fig. 2 is a view of the rear thereof.

My design includes the representation of a 15 trunk A of a tree, with root-branches B extending along the opposite edges of the upper portion of the bowl C, the trunk A extending upwardly upon the face of the spoon-handle and having diverging branches D extending 20 toward the edges of the handle, and the foliage E represented alongside the trunk upon the face of the handle and extending at e

around the opposite sides of the panel F produced upon the face of the handle near the upper edge thereof. On the rear of the handle 25 is produced the representation of the trunk, with the branches extending along the upper edges of the bowl of the spoon and with foliage at E' along the edges of the handle and extending at e' around the edges of the upper 30 portion of the handle, a tree G being produced on the back of the handle near its upper end, as shown in Fig. 2.

Having described my invention, what I claim as new, and desire to secure by Letters 35 Patent, is—

The ornamental design for a handle for spoons or similar articles as herein shown and described.

NEWTON H. ANDRUS.
